**LIQUID BLEACH DISTRIBUTOR FOR A
 WASHING MACHINE**
 Leendert Holleman, 5276 Linden Ave.,
 Long Beach, Calif.
 Filed Aug. 3, 1964, Ser. No. 386,937
 4 Claims. (Cl. 68—207)

This invention relates to a liquid bleach distributor for a washing machine, and particularly to a dispenser which may be attached to the agitator of an automatic washing machine and provides a device for automatically dispensing liquids, such as a bleach, into an automatic washing machine, and especially during the washing cycle of the machine.

An object of my invention is to provide a novel liquid bleach distributor which is mounted on the top of the washing machine agitator post, and which oscillates with that post during the washing cycle of the washing machine, and because of this oscillation outlet ports are caused to be opened to permit liquid bleach or other washing detergents to flow into the wash water during the washing cycle of the automatic washing machine.

Still another object of my invention is to provide a novel liquid bleach distributor in which free moving balls are provided within the distributor, the balls being caused to move with relation to the outlet holes in the bottom of the distributor, thus permitting liquid to flow out of the outlet holes during the time that the ball is not covering the outlet hole.

Still another object of my invention is to provide a novel liquid bleach distributor which is simple in construction, inexpensive to manufacture, and which can be readily mounted on the agitator post of the machine.

Other objects, advantages and features of invention may appear from the accompanying drawing, the subjoined detailed description and the appended claims.

In the drawing:

FIGURE 1 is a perspective view of a washing machine 40 with my liquid bleach distributor mounted on the agitator post.

FIGURE 2 is a transverse sectional view of the liquid bleach distributor mounted on the agitator post.

FIGURE 3 is a bottom plan view of the liquid bleach 45 distributor.

FIGURE 4 is a horizontal sectional view of the liquid bleach distributor.

FIGURE 5 is a fragmentary vertical view of a slightly modified form of liquid bleach distributor.

Referring more particularly to the drawing, the numeral 1 indicates a type of automatic washing machine which includes an agitator 2, and the central agitator post 3 driven by the mechanism of the washing machine. The agitator 2 and its post 3 are oscillated continuously 55 during the washing cycle of the machine, all of which is usual and well known in the art.

My liquid bleach distributor 4 consists of a circular outer wall 5 and an integral inner sleeve 6. The sleeve 6 is so shaped and sized that it will accurately and frictionally engage the upper end of the agitator post 3 so that the entire liquid bleach distributor will move with the agitator post, and particularly will oscillate with that post. An annular liquid containing reservoir 7 is formed in the upper portion of the liquid distributor between the wall 5 and the sleeve 6. A pair of distributing chambers 8-9 depend from the chamber 7 and are formed as an integral part of the distributor 4, and particularly the outer wall 5 and sleeve 6 thereof. Suitable holes or openings 10 are provided between the reservoir 7 and the dis-

2

tributing chambers 8-9, so that the liquid bleach or the like will continuously flow into these chambers. An outlet hole 11 and 12 is provided in the bottom walls of the chambers 8 and 9 respectively. These holes permit the liquid bleach to flow out of the distributor chambers and thence into the wash water. The bottom walls 13 of the chambers 8 and 9 are each inclined both radially and circumferentially towards the holes 11 or 12. The purpose of this inclination is to induce the check balls 14 and 15 to rest on the holes 11 and 12 respectively to prevent liquid from flowing out of these holes, except during the oscillating operation of the agitator 2, which by reason of this agitation will displace the balls 14 and 15 causing the balls to roll back and forth, and thus open or expose the holes 11 and 12 and permit liquid bleach to flow out of them. A filler cap 16 permits the reservoir 7 to be filled prior to each use of the washing machine.

In FIGURE 5 I have disclosed a slight modification in which a baffle plate 16 may be provided on the bottom of the distributor chambers 8 and 9 for the purpose of deflecting liquid inwardly towards the central agitator post 3.

Having described my invention, I claim:

1. A liquid bleach distributor for a washing machine comprising, a housing having a reservoir therein, and a pair of oppositely arranged distributor chambers communicating with the reservoir, each of said distributor chambers having an outlet hole therein, a free rolling ball in each of the distributor chambers adapted to rest in the outlet hole in one position of the parts.
2. A liquid bleach distributor for a washing machine comprising, a housing having a reservoir in the upper portion thereof and a pair of oppositely arranged distributor chambers depending from the reservoir and communicating therewith, each of said distributor chambers having an outlet hole in the bottom wall thereof, said bottom wall being inclined towards said outlet hole, and a free rolling ball in each of the distributor chambers adapted to rest in the outlet hole in one position of the parts.
3. A liquid bleach distributor for a washing machine comprising, a housing having a reservoir therein, and a pair of oppositely arranged distributor chambers communicating with the reservoir, each of said distributor chambers having an outlet hole therein, a free rolling ball in each of the distributor chambers adapted to rest in the outlet hole in one position of the parts, said housing including a central sleeve adapted to fit on the agitator post of the washing machine.
4. A liquid bleach distributor for a washing machine comprising, a housing having a reservoir in the upper portion thereof and a pair of oppositely arranged distributor chambers depending from the reservoir and communicating therewith, each of said distributor chambers having an outlet hole in the bottom wall thereof, said bottom wall being inclined towards said outlet hole, and a free rolling ball in each of the distributor cham-

bers adapted to rest in the outlet hole in one position of the parts,
said housing including a central sleeve adapted to frictionally fit on the agitator post of the washing machine.
